UNITED STATES PATENT OFFICE.

GUST HARMOUTH, OF YALE, OKLAHOMA.

PENCIL CLIP.

Application filed February 15, 1928. Serial No. 254,427.

This invention relates to clips for pencils and fountain pens, which are adapted to prevent them from slipping out of the vest pockets in which they are ordinarily carried; and it consists in providing the spring member of the clip with a ball bearing which permits it to slide easily on the material of the vest in the act of withdrawing the pencil from the pocket.

- 10 In the drawings, Fig. 1 is a side view of a pencil provided with a clip constructed according to this invention. Fig. 2 is a cross-section through the ball bearing, taken on the line 2-2 in Fig. 1, and drawn to a larger scale.
- 15 The pencil 5, or fountain pen, is provided with a tubular clip or attachment 6 which is sprung over it or otherwise attached to it. This clip has a spring member 7 which projects from one side of it and extends longitudinally of the pencil. This spring member has a cup 8 at its free end, and a ball 9 is mounted in the cup so as to rotate freely. The cup is a little larger than a hemisphere, and its edge 10 is pressed inwardly around
- 20 the ball in the cup so as to hold the ball in the cup, with one side of the ball projecting

from the cup towards the pencil. The spring member holds the ball pressed firmly against the outside of the pocket, and the ball facilitates the removal of the pencil from the pocket and also its replacement, and it prevents the material of the pocket from being torn or worn away, and permits the use of a stronger spring member, so that the pencil is held with great security.

What I claim is:

A clip for a pencil or pen, comprising a spring member having at one end means for attaching it to the pencil or pen, and having an integrally formed cup at its other end, 30 said cup being larger than a hemisphere, and a ball mounted to rotate freely in the cup with one side projecting therefrom, the other side of the ball being concealed within the cup and bearing centrally against the 35 bottom thereof, and the edge of the cup being pressed inwardly to retain the ball in place.

In testimony whereof I have affixed my signature.

GUST HARMOUTH.
